UNITED STATES PATENT OFFICE.

BENJAMIN D. CHAMBERLIN, OF ROCHESTER, NEW YORK, ASSIGNOR TO EASTMAN KODAK COMPANY, OF ROCHESTER, NEW YORK, A CORPORATION OF NEW YORK.

PHOTOGRAPHIC PRINTING MACHINE.

Application filed February 27, 1925. Serial No. 12,098.

This invention relates to photography, and more particularly to photographic printing machines. One object of my invention is to provide a platen moving mechanism by which good contact can be secured between a sheet of printing paper and a negative lying on the printing panel. Another object is to provide a toggle mechanism for moving the platen, separate toggles being provided for the platen sections. Another object is to distribute the pressure exerted by the toggle members at one point substantially centrally of the platen to different points over the area of the platen, and to thereby, in effect, provide a platen section which is rockable in all directions (for a limited distance) about the central supporting point. Another object is to provide platen sections with hinge-like connections to each other and to the machine frame which retain these parts together but permit sufficient lost motion between them to allow them to be individually compressed by their separate toggles. Another object is to provide connections between the toggles, whereby they may be differentially moved, that is, they move together through a portion of their stroke and one may be moved alone through a portion of the stroke. Another object is to provide connections between the toggles adapted to reduce friction to a minimum. Another object is to provide a cam and cam follower connection between the toggles for controlling their relative movement. Another object is to provide a conveniently located toggle operating mechanism. Another object is to provide such a mechanism with a handle which may be readily fastened at different angles to suit the needs of the individual operator. Another object is to provide a platen which may be moved from the panel a sufficient distance to permit a clear view thereof vertically from above the panel. Still another object is to provide a toggle operated two part platen in which one section contacts with the panel in advance of the other, and still other objects will appear hereinafter from the following specification the novel features being pointed out in the claims at the end thereof.

It is desirable in printing machines to secure good contact between the negative and printing paper for professional work and this is difficult to obtain in the large sizes such as 10" x 12" and 14" by 16". Negat-

tives vary considerably in thickness due to different thicknesses of glass and film base, the printing papers differ in thickness and the masks and border tinting devices also vary in thickness: so that altogether the thickness of the pile between the platen and the printing panel may in extreme cases be as great as $\frac{3}{8}$ of an inch. This, of course, greatly increases the difficulty of obtaining good contact. In addition the glass printing panel is frequently not a plane surface. My platen and operating mechanism are particularly designed to overcome these difficulties.

Coming now to the drawings wherein like reference characters denote like parts throughout:

Fig. 1 is a side elevation of a printing machine constructed in accordance with and illustrating one embodiment of my invention;

Fig. 2 is a plan view thereof;

Fig. 3 is a fragmentary section on line 3—3 of Fig. 2;

Fig. 4 is a perspective view of a toggle yoke;

Fig. 5 is a section on line 5—5 of Fig. 2;

Fig. 6, 7 and 8 are diagrammatic views of the toggles showing certain links in different positions;

Fig. 9 is a fragmentary section of an operating handle and mount;

Fig. 10 is a side elevation of a part of the mechanism shown in Fig. 9;

Fig. 11 is an enlarged detail side elevation of the toggle connecting mechanism;

Fig. 12 is an enlarged plan view of parts of the platen operating mechanism; and

Fig. 13 is an enlarged detail plan view of the toggle spring.

The present embodiment of my invention comprises a table top 1 in which there is mounted a panel 2, through which light passes from the printing lamps 3 inside of the lamp house 4. Legs 5 support the table top 1. A support 6 extends up from the table top for supporting the platen and the platen operating mechanism.

The platen, designated broadly as 7 is operated by means of two toggle members 8 and 9 each pivoted at 10 to the support 6 and having a sliding pivotal connection at 11 with the platen.

As best shown in Figs. 2 and 5, I preferably form my platen 7 of two castings 12 and

and 13 which are connected by a hinge-like joint consisting of arms 14 from section 12 which have elongated apertures 15 through which stub shafts 16 pass, these shafts being supported by lugs 17 on section 13. Section 13 has arms 18 with elongated slots 19 engaging a shaft 20 supported by the support 6. Thus, while these parts are hinged together the parts are permitted to move or rock considerably with respect to each other. I also prefer to face sections 12 and 13 with felt, plush, or other compressible material 21.

Bearing in mind that the sections 12 and 13 are individually rockable with respect to each other, the mechanism by which they are individually pressed against the panel will now be described. Blocks 22 are cast at spaced intervals on section 12. These blocks 20 have angular faces 23 supporting springs 24 to which a yoke 25 is attached at their central parts, and a shaft 26 passes through the yoke 25 and carries rollers 27 which engage the guideways 28 formed in lugs 29 which are preferably a part of section 12. Obviously pressure applied to shaft 26 exerts pressure upon yoke 25 and springs 24, which in turn, distributes the pressure upon blocks 22.

30 In order to raise the platen, I prefer to provide roller stops in the form of pins 27' passing through the guideways 28 just above the normal position of rest for the rollers 27, which by contacting with pins 27' raise 35 the platen.

Toggle 8 preferably consists of two pairs of links, 30-30 and 31-31. The former links 30-30 being carried by shaft 26, and being attached to each other by studs 32. 40 Links 31-31 are carried by shaft 10, and one of the links 31 is attached at 33' to link 33. Link 33 is pivoted at 34 to an arm 35 carried by a shaft 36 supported by bearing 37 in support 6 and 38 in bracket 39.

45 An operating lever 40 is affixed to shaft 36 and is provided with a handle 41. By moving handle 41 the toggle 8 is moved.

Toggle 9 consists of a lower link 42 pivoted to yoke 43 by shaft 44 supported upon 50 springs 45 which rest on blocks 46 of platen section 13. This section carries guideways 47 in lugs 48 with which rollers 49 on shaft 44 cooperate. Roller stops 49' pass through guideways 47. There is only a single lower link 42 which passes freely between links 30-30. A pair of upper links 50-50 are attached to link 42 by a pivot 51 and these links are free to move between links 31-31.

Link 42 differs from the other links in 60 having two stops 52 and 53, the former limiting the movement of toggle 9 outwardly, stopping the parts in the position shown in Fig. 1. The other stop, 53 is carried on the end of an arm 54, one side of which forms 65 a cam 55. The major portion 56 of the cam

is concentric with shaft 10 and the remaining portion 57 is substantially concentric with pivot 51. Cam 55 is a guideway for the cam follower 58 in this case a roller carried by the shaft 59 extending between 70 brackets 60 attached to links 31-31.

I prefer, as shown in Figs. 11 and 12 to make the stop a resilient or compressible one to reduce jar and noise. Consequently the stop 53' may consist of a leaf spring 54' 75 attached to cam 56 by screws 56' and countersunk in cam 56 so as to provide a smooth guideway for roller 58. A curved end 57' may be suitably shaped to engage roller 58.

Links 31-31 are connected together by a 80 yoke 61. This permits links 31-31 to swing about links 50-50 until engaged by a yoke 61 after which both sets of links are moved together (see dot and dash lines Fig. 1). When, however, the links 31-31, 50-50 85 separate, their relative movement is controlled by the cam 55 and roller 58. As roller 58 moves on cam portion 56 (that is concentric with shaft 10) obviously toggle 9 can not move from its operative position, 90 as shown in full lines Fig. 1, since to do so arm 54 would have to move upwardly. Therefore toggle 9 always reaches its operative position before toggle 8, and is held so until roller 58 reaches cam portion 57 (Fig. 95 6) at which position links 42-50 may swing to their inoperative position, successive positions being indicated in Figs. 7 and 8. In Figs. 6, 7 and 8 links 50 lie directly under links 31, being engaged by yoke 61. 100 Thus the movement of toggle 9 is controlled in both opening and closing by toggle 8, and the roller 58 and cam 55 form a lost motion connection between the two toggles.

I prefer to use a lifting spring 70 to counterbalance the weight of the platen 7 and by using a spring of the proper strength the mechanism may be made to function with very little effort. Spring 70 is preferably arranged as shown in Fig. 13 with the ends 110 coiled about shaft 20 the central portion being looped about toggle link 42 being retained beneath the pin 71, and the ends of the spring being caught upon pins 72 of arm 73 which support the platen hinge pintle or 115 shaft 20.

In Figs. 9 and 10 I show a preferred form of operating handle, arranged so that the operating handle position may be altered to suit the individual operator. In this embodiment the handle 41 is carried by the arm 40 as above described, but this arm has a bearing 80 which may turn upon shaft 36. A segment 81 carrying apertures 82, and having an aperture 83 surrounding shaft 36 is keyed 120 to the shaft at 84 so as to turn with it. Arm 40 is tapped at 85 to receive the screws 86 which may be easily removed or inserted so as to position the handle 41 at any desired angle; a tall operator generally preferring 130

to place the handle in a substantially vertical position (when the platen is lowered) where-as a shorter operator may lower the handle to the desired angle.

- 5 In side of the lamp house 4 there are a series of slots 90 adapted to receive sheets of light diffusing material such as ground glass, opal glass or the like. The slots are carried in a rack 91 and may be reached 10 through a door 91' operated through a handle 92 when the rack is in the proper position. The position of the rack is adjusted in the following manner: Rack 91 is supported by straps 93 which carry the lamp plate 94 upon which the sockets 95 are mounted and the frame thus formed by rack 91 as the top, plate 94 as the bottom and straps 93 as the sides is slideable upon rollers 96 carried by bolts 97. These rollers engage 15 the edges 98 of straps 93. One strap has a rack 99 engaged by a latch 100 pressed by spring 101 into the rack. The latch is pivoted to a shaft 102 operable by a handle 103 outside of the casing. A second handle 20 104 through shaft 105 moves lever arm 106 connected by a link 107 pivoted at 108 to the lever and at 109 to rack 91. Thus when latch 100 is released from the rack 99 handle 104 may be moved to adjust the lamps 3 and the rack 91, the uppermost position being shown in dashed lines Fig. 1 and the lowermost position being shown in dot and dash lines in the same figure. The light 25 intensity may be altered by the diffusing material alone, or by altering the distance between the lamps 3 and the printing panel 2 or by adjusting both the lamps and the diffusing material.
- 30 It is to be understood that while the machine illustrated in the drawings and herein described is a preferred embodiment of my invention nevertheless numerous other embodiments may be made and I therefore desire to include as within the scope of my invention all such embodiments as may come within the terms of the claims at the end of this specification.
- 35 Having thus described my invention, what I claim as new and desire to secure by Letters Patent is:
1. In a printing machine, the combination with a panel, of a platen movable thereover, means for moving the platen including a pair of toggles, and cooperating members on the toggles adapted to cause one toggle to operate in advance of the other.
2. In a printing machine, the combination with a panel, of a platen movable thereover, means for moving the platen including a pair of toggles, means for operating one toggle, and cooperating members carried by the toggles for transmitting motion from one toggle to the other.
3. In a printing machine, the combination 40 with a panel, of a platen movable thereover,

means for moving the platen including a pair of toggles, each toggle including upper and lower parts, and means carried by the upper part of one toggle and the lower member of the other toggle for permitting one toggle to be moved by the other.

4. In a printing machine, the combination with a panel, of a platen movable thereover, means for moving the platen including a pair of toggles, means for moving the toggles relative to each other including a cam on one toggle and a cam follower carried by the other toggle.

5. In a printing machine, the combination with a panel, of a platen movable thereover, means for moving the platen including a pair of toggles, means for moving the toggles differentially relative to each other including a cam on one toggle and a cam follower on the other, the cam being shaped to limit the total movement of the toggles.

6. In a printing machine, the combination with a panel, of a platen movable thereover, means for moving the platen including a pair of toggles, said toggles including a plurality of links, a link on one toggle having a stop to limit the movement of both toggles.

7. In a printing machine, the combination with a panel, of a platen movable thereover, means for moving the platen including a pair of toggles, a cam on one toggle and a cam follower on the other, the cam having one portion shaped to move the toggle together when the cam and follower cooperate at one portion of the cam, and having another portion shaped to permit one toggle to move while the other toggle remains stationary when the cam is engaged by the follower at the other portion of the cam.

8. In a printing machine, the combination with a panel, of a platen movable thereover, means for moving the platen including a pair of dissimilar toggles, means for moving one toggle, and means carried by this toggle for engaging and moving the other toggle differentially with respect to the first mentioned toggle.

9. In a printing machine, the combination with a panel, of a platen movable thereover, means for moving the platen including a pair of toggles, and a common shaft about which one end of each toggle may turn.

10. In a printing machine, the combination with a panel, of a platen movable thereover, means for moving the platen including a pair of toggles, and a shaft adapted to support one end of each toggle, parts on the toggles being adapted to cooperate when the first toggle is moved whereby both toggles are moved between an operative and an inoperative position.

11. In a printing machine, the combination with a panel, of a platen movable thereover, means for moving the platen including

- 4
- toggle members, a frame and means on the frame for supporting one end of the toggles, and resilient connections between the platen and the other ends of the toggles.
5. 12. In a printing machine, the combination with a panel, of a platen movable thereover, means for moving the platen including toggle members, a frame and means on the frame for supporting one end of the toggles, and spaced resilient members carried by the other ends of the toggles for engaging the platen at spaced intervals.
10. 13. In a printing machine, the combination with a panel, of a platen movable thereover having guideways formed therein, means for moving the platen including toggles, a frame adapted to support the toggles at one end, and connections between the other ends of the toggles and the guideways.
15. 14. In a printing machine, the combination with a panel, of a platen movable thereover having guideways formed therein, means for moving the platen including toggles, a frame adapted to support the toggles at one end, and connections between the other ends of the toggles and the guideways said connections including spring members positioned to normally hold the toggles at the ends of the guideways.
20. 15. In a printing machine, the combination with a panel of a platen movable thereover, a guideway included in the platen, means for operating the platen including a toggle, a frame for supporting one end of the toggle, the other end of the toggle being supported in the guideway, and means for limiting the movement of the toggle in the guideway.
25. 16. In a printing machine, the combination with a panel of a platen movable thereover, a guideway included in the platen, means for operating the platen including a toggle, a frame for supporting one end of the toggle, the other end of the toggle being supported in the guideway, the part carrying the toggle end being adapted to move in the guideway, and a spring adapted to hold the part normally at one end of the guideway, said spring permitting the toggle to move the part in the guideway toward the platen.
30. 17. In a printing machine, the combination with a panel of a platen movable thereover, a guideway included in the platen, means for operating the platen including a toggle, a frame for supporting one end of the toggle, the other end of the toggle being supported in the guideway, a yoke supported by the toggle end engaging the guideway and spaced springs supporting the ends of the yoke, the guideway in the platen being located between the springs.
35. 18. In a printing machine, the combination with a panel, of a platen movable thereover said platen consisting of two sections hinged together, means for operating the platen including a pair of toggles, one toggle connected to each platen section, means for moving the platen sections differentially through the toggles, the relative movement of the toggles being controlled by a cam and a cam follower.
40. 19. In a printing machine, the combination with a panel, of a platen movable thereover, means for moving the platen including a pair of toggles, a support for one end of the toggles and a slidable connection between the other end of the toggles and the platen.
45. 20. In a printing machine, the combination with a panel, of a platen movable thereover, means for moving the platen including a pair of toggles, a support for one end of the toggles and a slidable connection between the other end of the toggles and the platen, said slideway being disposed at an angle to the force exerted by the toggles.
50. 21. In a printing machine, the combination with a panel, of a platen movable thereover, means for moving the platen including two toggles, a link of one toggle having two stops, one for limiting the movement of one toggle and the other for limiting the movement of the other toggle.
55. 22. In a printing machine, the combination with a panel, of a platen movable thereover, means for moving the platen including two toggles, said toggles having cooperating members through which the toggles may be moved together and through which one toggle may move alone as the platen is moved relative to the panel.
60. 23. In a printing machine, the combination with a panel, of a platen movable thereover, means for moving the platen including two toggles, each toggle being made up of a plurality of links, one toggle consisting of pairs of spaced links adapted to permit the links of the other toggle to move between the spaced links as the platen is moved relative to the printing panel.
65. 24. In a printing machine, the combination with a panel, of a platen movable relative to the panel, means for moving the platen including a toggle mechanism, a guideway carried by the platen, and a member adapted to move in the guideway carried by the toggle, a spring normally moving the member toward one end of the guideway, said spring being adapted to be tensioned by the toggle.
70. 25. In a printing machine, the combination with a panel, of a platen movable relative to the panel, means for moving the platen including a toggle mechanism, a guideway carried by the platen, and a member adapted to move in the guideway carried by the toggle, and means associated with the guideway for limiting the movement of the member movable in the guideway in two directions.

26. In a printing machine, the combination with a panel, of a platen movable relative to the panel, means for moving the platen including a toggle mechanism, a guideway carried by the platen, and a member adapted to move in the guideway carried by the toggle, means associated with the guideway for limiting the movement of the member movable in the guideway in two directions, and a spring tending to hold the member movable in the guideway at one end thereof. 65
27. In a printing machine, the combination with a printing panel, of a platen movable thereover, means for moving the platen including a pair of toggles, and means on one toggle for preventing a toggle from moving during a part of the movement of the other toggle. 70
28. In a printing machine, the combination with a printing panel, of a platen movable thereover, means for moving the platen including a pair of toggles, and mechanism including an arm carried by one toggle and cooperating with the other toggle by which the toggles will be moved together and by which one toggle will be moved while the other toggle will be held stationary as the platen is moved to or from the panel. 75
29. In a printing machine, the combination with a printing panel, of a platen movable thereover, means for moving the platen including a pair of toggles, a power operated means for moving one toggle through a definite stroke to move the platen to or from the panel, and mechanism between the two toggles for moving the other toggle, during a portion of the stroke of the first toggle. 80
30. In a printing machine, the combination with a panel, of a platen movable thereover, said platen including two sections movable relative to each other, means for moving the platen sections including toggles, and means associated with the toggles and operated thereby for applying pressure to the platen sections at four spaced locations. 85
31. In a printing machine, the combination with a panel, of a platen movable thereover, said platen including two sections movable relative to each other, means for moving the platen sections including toggles, and means associated with the toggles adapted to contact with the platen sections at a plurality of spaced locations when the toggles are moved. 90
32. In a printing machine the combination with a panel, of a platen movable thereover, a toggle for operating the platen, a support for holding one end of the toggle, and a slideway on the platen with which the other end of the toggle cooperates. 95
33. In a printing machine, the combination with a panel, of a platen movable thereover, said platen consisting of two relatively movable parts, means for moving the platen parts including two toggles, each toggle consisting of a pair of links, spacers for holding the pairs of links of one toggle apart a distance greater than the width of the other toggle links whereby the last mentioned toggle may move between the spaced links of the first mentioned toggle. 100
34. In a printing machine, the combination with a panel, of a platen movable thereover, said platen consisting of two relatively movable parts, means for moving the platen parts including two toggles, each toggle consisting of a pair of links, the links of one toggle being spaced to permit the links of the other toggle to function therebetween, stops for limiting the movement of the toggles, both of said stops being carried by a single link of one of the toggles. 105
35. In a printing machine, the combination with a panel, of a platen movable thereover, said platen consisting of two relatively movable parts, means for moving the platen parts including two toggles, each toggle consisting of a pair of links, stops for the toggles, one stop consisting of an abutment adapted to be engaged by a toggle link, said abutment having a resilient member adapted to reduce the shock of the contact between the abutment and toggle member. 110
36. In a printing machine the combination with a panel, of a two part platen movable thereover, platen moving mechanism including toggle members each comprising a pair of toggle links, one link carrying a cam, and another link a cam follower, the cam being shaped to cause the toggles to move together through a portion of an operating stroke wherein the cam follower moves over one portion of the cam, and being shaped to hold one toggle stationary while the other moves as the cam follower moves over another portion of the cam. 115
37. In a printing machine, the combination with a panel, of a two part platen movable thereover, platen moving mechanism including toggle members each comprising a pair of toggle links, and means including a power operated link pivotally attached to one toggle link for controlling the movement of all of the toggle links. 120
38. In a photographic printing machine, the combination with a panel, of a platen movable thereover, means for moving the platen comprising a pair of toggle members, a handle for operating the platen, connections between the handle and one of the toggles whereby one toggle may be operated by the handle, and slidable connections between the two toggles whereby the toggles may be differentially operated. 125
39. In a photographic printing machine, the combination with a panel, of a platen movable thereover, means for moving the platen comprising a pair of toggle members,

- each consisting of a plurality of links, a handle for operating the platen, connections between the handle and one link of a toggle, and operative connections between the two 5 toggles whereby the handle may be moved to move one toggle, and the other toggle may be moved through the operative connections between the toggle members.
40. In a printing machine, the combination 10 with a panel, of a platen movable there-over means for moving the platen including a pair of toggles, mechanism for moving the toggles including a power operated member connected to one toggle, a lost motion connection between the two toggles, the power 15 driven toggle being adapted to move the other toggle through the lost motion connection through a portion of its movement.
41. In a printing machine, the combination 20 with a panel, of a platen movable relative to the panel, means for moving the platen including a pair of toggles, one toggle consisting of two pairs of links, spacers for holding the links at a fixed separation, the spacers being of greater width than the 25 width of the other toggle whereby the last mentioned toggle may move between the spaced links of the first toggle.

Signed at Rochester, New York this 24th day of February, 1925.

BENJAMIN D. CHAMBERLIN.
